WELDER

William H. Martin, Pleasant Ridge, Mich., as-
signor to Progressive Welder Company, a cor-
poration of Michigan

Application February 19, 1940, Serial No. 319,589

2 Claims. (CL. 218—4)

My invention has for its object to provide a means for insuring a high, electric contact pressure of an electric conductor against a movable, electrode-supporting member to reduce the contact resistance to the flow of a current, when directed to the electrode.

The invention provides a pressure means, which may be operated by fluid, under pressure, and located at the pivot point of the electrical connections for producing, pneumatically, a high, electric contact pressure after the electrodes have been, manually, placed in position, with reference to an object through which the current is to be directed.

The invention may be utilized in connection with electrically-operated and manually-manipulated devices of different forms, and, to illustrate a practical application of the invention, I have selected a welder as an example of the various structures containing the invention and shall describe the selected structure hereinafter. The particular structure selected is shown in the accompanying drawing.

Fig. 1 of the drawing illustrates a side view of a welder. Fig. 2 illustrates a view of a section taken on the plane of the line 2—2, indicated in Fig. 1.

In the form of welder shown in the figures, a pair of electrodes 10 and 11 are mounted on the ends of the arms 12 and 14 for engaging opposite sides of the work to produce a weld. The welder is provided with a cylinder 15, which is mounted on an extension 16 of the arm 14, for relatively manipulating the arm 12, to cause the electrodes 10 and 11 to press against the work. The piston of the cylinder 15 is connected, by means of a link 17, to a projection 18 of the arm 12. The arm 12 is pivotally connected to the arm 14, by the piston rod 20, which is located in a sleeve 21 and washers 22 of insulating material to prevent conduction at the point of connection of the arms. The arm 12 has a bifurcated extension, having ears 24, and the arm 14 is provided with a web 25, located between the ears of the arm 12. The terminals 27 of the electric conductors are provided with bosses 28, which extend into the ears 24 of the bifurcated extension of the arm 12. One of the bosses 28 extends through one of the ears 24 and, electrically, contacts with the web 25 of the arm 14, while the other terminal 27 shoulders against the other ear 24 of the arm 12, whereby the current from the conductors 30 flows through the arms 12 and 14, the electrodes 10 and 11, and the work 29. Except where the terminals 27 contact with the

parts of the arms 12 and 14, the terminals are insulated by the sleeves 31 and the washers 32, to prevent short-circuiting of the welding current.

One end of the piston rod 20 is threaded and provided with clamping nuts 34, while the other end of the piston rod is secured to a piston 37, which is located in the cylinder 35, by the nut 36. The nuts 34 may be adjustably secured on the piston rod to produce a desired looseness of the joint to enable ready manipulation of the arm in locating the electrodes in proper positions on the work and yet to tightly clamp the parts of the joint when the air, under pressure, is directed to the cylinder 35.

15 A pipe 38 extends to the cylinders 15 and 35. The pipe 38 may be connected, by a valve 40, to a source of supply of air pressure, through a pipe 41. The valve is electromagnetically operated, by means of a solenoid 42, when the switch 44 is closed, to connect the solenoid 42 with a source of supply of electric current. The pressure, which is, thus, transmitted to the cylinders 15 and 35, causes the arms 12 and 14 to engage opposite sides of the work, by reason of the fact that the arms 12 and 14 are free to move, and, upon engagement of the electrodes with the work, the pressure builds up in the cylinder 15, and is transmitted to the cylinder 35, which causes the plane surfaces of the arms 12 and 14 to be clamped against the plane contacting surfaces of the terminals and reduce the resistance to the flow of the welding current from the conductors 30, to the electrodes 10 and 11, and through the work.

35 This enables, by reason of the free pivotal movement of the arms, ready placement of the electrodes in position, with reference to the work. When the electrodes have been placed in position by the operator, and the cylinders connected to the source of air, under pressure, the resistance to flow of the current, to the electrodes, is greatly reduced by the operation of the cylinder 35, which tightly clamps the plane contacting surfaces of the terminals and the arms together.

45 I claim:

1. Welding apparatus comprising a frame, welding electrodes mounted on said frame, means for actuating said electrodes between work-engaging and released positions, means including a pair of conductors for completing an electric circuit to said electrodes, means for pivotally mounting said frame relative to at least one of said conductors, with conductive surfaces on said frame and said one conductor in engagement with each other, means constructed and ar-

ranged for cooperation with said mounting means and operable by said actuating means for selectively clamping or unclamping said frame with respect to said one conductor thereby permitting or preventing, respectively, relative pivotal movement between said frame and said one of said conductors and, when clamped, urging said surfaces together.

2. The structure of claim 1 wherein said frame comprises a pair of pivotally connected arms each of which carries one of said electrodes, and wherein the pivotal axis of said arms is coincident with the pivotal axis between said frame and said one conductor.

WILLIAM H. MARTIN.
